UNITED STATES PATENT OFFICE.

CHARLES W. BUTTRICK, OF SPRINGFIELD, ILLINOIS.

MOTOR FOR RAILWAY-GATE EQUIPMENT.

Application filed April 17, 1922. Serial No. 553,623.

The invention relates to hydraulic motors employing fluids in motion to actuate gates or other mechanism and is primarily intended to be installed at places where high-ways cross railway tracks; but is obviously adapted for use in various and different situations.

For convenience I will describe an installation using oil as the flowing fluid, but it is to be understood that any other suitable fluid may be used. Oil is specially suitable for the purpose because it is relatively cheap and obtainable everywhere, is not easily volatile or explosive, and is safe and dependable under all ordinary conditions of use.

The purposes of the invention are: to provide a reservoir containing a supply of oil in conjunction with a pipe system directing the flow of oil from the reservoir through the system; to provide means for maintaining practically constant air pressure on the oil in the reservoir; to provide in co-operative relation to each other a source of supply of fluid under pressure, duplex pipe lines receiving in the first instance, a controlled supply of fluid from said source of fluid supply, air domes at the terminals of the respective pipe lines remote from the source of supply and receiving fluid from the respective pipe lines, an even number of sets of car-wheel-actuated pump-units receiving fluid from the pipe lines, each pump-unit comprising duplex pumps, motors receiving fluid from the duplex pipe lines, air chambers receiving fluid from said motors, and gate mechanism actuated by said motors, one of said duplex pumps in each pump-unit being effective to propel fluid through one pipe line into one end of a motor cylinder and the other duplex pump of the same pump-unit being effective to propel fluid through the other pipe line of the duplex into the other end of the same motor cylinder; and to provide other new and useful structural details.

With these ends in view, the invention consists in the novel features of construction and combinations of parts shown in the accompanying drawings, to which reference is hereby made, and said invention will now be fully described and finally recited in the claims.

Figure 1 is a top plan view of a fluid motor and appurtenances embodying my invention; Fig. 2 is a fragmentary vertical sec-

tion taken on the line 2—2 of Fig. 1; Fig. 3 is a vertical section taken on the line 3—3 of Fig. 1; Fig. 4 is an enlarged vertical axial section through one air chamber taken on the line 4—4 of Fig. 1, and shows details of the valve connected with the air chamber; Fig. 5 is a diagrammatic vertical axial section through the reservoir, some of the parts being shown in elevation; Fig. 6 is an enlarged side elevation of one air dome; Fig. 7 is a vertical section through the same air dome, taken on the line 7—7 of Fig. 6, and Fig. 8 is a diagram showing motors, pump-units, pipe line, air domes, and a reservoir, in operative relation to each other.

The same reference numerals and letters designate the same parts in all the views.

The motor, designated as a whole by the letter M, comprises a cylinder 40, cylinder heads 41 and 42, secured at the respective ends of the cylinder, a piston 43 slidable in the cylinder, spiders 44 and 45 fixed in the cylinder; each spider having elongated longitudinally bored hubs; and two tubular piston rods 46 and 47 in line with each other, one slidable in the longitudinal bore of the spider 44 and the other slidable in the longitudinal bore of the spider 45.

The piston 43 has a longitudinal bore 48, and counter bores 49 and 50 to receive the inner ends of the respective piston rods.

A transverse hole 51 extends through the rod 46 adjacent to the inner end of the spider 44 and a similar transverse hole 52 extends through the rod 47 adjacent to the outer end of the spider 45.

When the gate 18 (Fig. 8) is extended in closed position, the piston 43 will occupy the position shown in full lines in Fig. 3 and when the gate is raised in open position, the piston will be in the position indicated by dotted lines in Fig. 3. Oil under pressure, applied by one or more pump-units as hereinafter described, is admitted into the cylinder 40 through an opening 56 and acts on the left-hand end of the piston 43 to slide it to the right; and similarly, oil under pressure, applied by one or more pump-units enters through the opening 55 and acts on the right-hand end of the piston 43 to slide it to the left.

After pressure has been applied to move the piston 43 in one direction it is necessary to equalize the pressure on both ends of the

piston so that it will be free to move in either direction. For this purpose I provide the leak openings 51 and 52 in the respective tubular stems 46 and 47. When the parts 5 are in the position shown in Fig. 3 if the greater pressure is on the right-hand end of the piston 43, oil entering the hole 51 will flow through the tubular stems 46 and 47 and will be discharged through them until 10 the pressure on both ends of the piston is the same. Since oil is practically non-compressible it is necessary to provide means for reducing the volume of oil in one part of the cylinder according to the increase in 15 the volume of oil in the other part of the same cylinder. This result is effected by an equalizer which will now be described.

The equalizer and appurtenances.

20 The equalizer (Fig. 2) comprises pipes 57 and 58 delivering oil through the respective openings 55 and 56 into the cylinder 40; air tanks 59 and 60 communicating with the interior of the cylinder 40 through pipes 25 61 and 62 attached at the respective ends of the cylinder and conveying oil from the cylinder into the respective tanks; a valve 53 controlling communication between the chamber 59 and the pipe 61; a valve 54 controlling communication between the chamber 60 and the pipe 62; diaphragms 63 and 64, preferably in the form of corrugated copper disks, enclosed in suitable casings 65 and 66; a bar 67 having its ends brazed 30 at the centers of the respective corrugated disks 63 and 64 and slideable in hubs 68 at the centers of the inner members of the respective casings 65 and 66; a lateral pipe 69 permitting inward and outward flow of 35 oil through the pipes 57 and 69 into and from the chamber 71; a lateral pipe 70 permitting inward and outward flow of oil through the pipe 58 and 70 into and from the chamber 72; an arm 73 fixed on the bar 40 67 midway between its ends; and a horizontal rod 74 (Figs. 1 and 2) fixed on the arm 73 and having its terminals operatively connected with the respective levers 75 and 76 which are fixed on the stem 77 of the valve 53 (Fig. 4) and on a similar stem (not 45 shown) of the valve 54. When the arm 73 is in its intermediate or neutral position as shown in Fig. 2, the piston 43 will be adjacent to one end of the spider 45, or adjacent to one end of the spider 44, as the case 50 may be; the pressure will be equal on both ends of the piston and the pressure on both diaphragms 63 and 64 will be equalized by transference of oil through the tubes 46 and 55 47 as already described and both valves 53 and 54 will be partly open, there will be equilibrium of the oil in the cylinder.

60 Valves 53 and 54 adjacent to the respective air chambers 59 and 60 control communication between the air chambers and the pipes 65

61 and 62 at the respective ends of the cylinder 40. Both valves are alike, except that one is right and the other left; so a description of one will suffice for both. The valves 53 and 54 act reversely; that is to say, when 70 the valve 53 is completely open, the valve 54 will be completely closed and when the valve 54 is completely open, the valve 53 will be completely closed. Details of the valve 53 are shown in Fig. 4 and will now 75 be described. The valve body 53 is a globular hollow casting suitably connected with the air chamber 59 and the pipe 61. A transverse shaft 77 oscillates in suitable bearings in the valve body and extends outwardly 80 beyond the valve body. A lever 75 is fixed on the shaft 77 and is pivotally connected with the rod 74. A slotted arm 131 is fixed on the shaft 77. A valve stem 132 is connected with the arm 131 by a pin 133. A 85 disk 134 is fixed on the stem 132, and engages on a valve seat 135 in the valve body. There are two spiders 137 in the valve body and each has a central hole in which the valve stem 132 slides.

90 When the pressure of oil in the chamber 72 acts on the diaphragm 64 to move the bar 67 to the right (Fig. 2) the arm 73 carried by the bar will cause the rod 74 to push the lever 75 to the right, with the result that 95 the arm 131 will turn downwardly and pull on the stem 132 to withdraw the disk 134 from the valve seat 135, thereby permitting excess of oil from the right-hand half of the cylinder 40, entering the valve through the 100 pipe 61 to go into the air chamber 59 against the air pressure therein thus avoiding excessive pressure in the cylinder 40 and when the pressure is reduced to normal, reverse movement of the lever 75 effected by the arm 105 73 moving to the left, responsive to the pressure of oil in the chamber 71 against the diaphragm 63, will result in replacing the disk 134 on the seat 135.

110 A rack bar 80 pivotally connected with the piston rod 40, engages with a suitable gear 86, to operate the driven mechanism.

The motor is actuated by wheel-actuated pump-units 20, each of which consists of two oppositely acting pumps 27 and 28, one effective to force fluid into one end of the motor cylinder when the operating train is going in one direction, and the other effective to force fluid into the other end of the motor cylinder when the operating train 115 is going in the opposite direction.

120 In order to describe clearly the mode of operation of the motors M, I have indicated conventionally, in Fig. 8, red pumps 27 and black pumps 28; and have indicated by broken and dotted lines the red pipes 22 and 26 supplying fluid to the red pumps, and have indicated by solid lines the black pipes 21 and 25 which supply fluid to the black pumps.

A preferred installation embodying the present invention is shown diagrammatically in Fig. 8. The installation comprises two railway tracks 13 and 14, a reservoir 15 containing oil under air pressure, to supply loss and maintain a proper supply of oil throughout the system; gate stand 16 and 17; motors M; four sets of pump-units 20, two sets adjacent to each track, each pump-unit consisting of duplex pumps 27 and 28 operated by a lever 112 actuated by the flanges of car wheels running on the track rails 13 or 14, as the case may be; duplex pipe lines 21 and 22; 23 and 24; and 25 and 26; operatively connecting the reservoir the pump-units and the motors. The wheel-actuated duplex pumps 27 and 28 are so constructed and arranged that when the pump 27 of any unit 20 is active, the complementary pump 28 of the same unit will be ineffective; and reversely, when the pump 28 of the same unit is active the pump 27 will be ineffective. All the pumps 27 of one series of pump-units propel oil entering one end of the corresponding motor cylinder 40; and all the pumps 28 of the same series propel oil entering into the other end of the motor cylinder. The flanges of the wheels of cars running on the track rails in one direction actuate the respective levers 112 to operate the red pumps in succession; and the flanges of the car-wheels running in the opposite direction on the same track rails act on the same levers 112 to operate the black pumps 28, to deliver fluid into the other end of the same motor cylinder. The two pumps 27 and 28 comprised in a single pump-unit 20 are duplex pumps in that they are similar in construction and co-act in such manner that when one is effective the other is ineffective; and similarly red pipe lines 21 and 22; 23 and 24; and 25 and 26, are duplex pipe lines, in that they admit of the surge of oil from the red pumps into one end of the cylinder of the motors M, to effect closing of the duplicate gates 18 and 19; and admit of the surge of oil from the black pumps 28 into the other end of the cylinder of the same motors M, to effect opening of the same duplicate gates.

I have shown four sets of pump-units, each set comprising four pump-units, but each set may comprise a greater or a less, even number of pump-units.

Inasmuch as there are a number of pump-units in each set it is obvious that successive increments of fluid will be forced into the motor cylinder by successive actions of the pumps and the pressure in the cylinder will be cumulative, thereby avoiding abrupt action of the motor and consequent shock and strain on the mechanism. Immediately following the operating of any pump-unit of the system, the compressed air in the reservoir 15 and the air cushions in the air

dome 136 will be effective to equalize fluid pressure throughout the system.

The reservoir 15 is preferably an air-tight cylinder of boiler plate, adapted to contain a volume of oil sufficient to compensate for leakage throughout the system; and a volume of compressed air above the oil, effective to maintain practically constant pressure throughout the system.

The reservoir is equipped with a pipe 127, 75 in communication with the interior of the reservoir and with the elements 150 and 151 of the pipe system. A valve 152 controls the flow of oil in the pipes 127 and 150; and a similar valve 153 controls the flow of oil 80 in the pipes 127 and 151. The valves 152 and 153 (Fig. 5) open outwardly in order that if the pressure in the pipes 150 and 151, or either of them is less than normal, the valve or valves will open to admit oil 85 from the reservoir into either pipe or both pipes, as the case may be, to replace lost oil and thereby restore equilibrium throughout the pipe line system.

The check valves may be of any approved construction adapted to operate as described. The operating of the pump-units by the wheels of cars running on the railway track will cause the motor to operate as already 90 described.

Air domes are provided at the terminals of the respective pipe lines which are remote from the air reservoir. The air domes are all alike so only one need be described. The air dome connected with the pipe line 100 26 comprises a dome-shaped casting 136 (Figs. 6, 7, and 8) open at one end and having a circular flange 137 at the open end. An elbow 138 has flanges 139 and 140. The flange 139 is connected with the flange 137 by bolts 141; and the flange 140 is connected with a flange 142 on the pipe 26 by bolts 143. When the pipe lines are full of oil, a volume of air will be trapped in each dome 136, and in case of excessive pressure 110 in the pipe, the trapped air in the dome will be compressed to a degree sufficient to avoid undue strain on the pipes.

Division having been required in this case, reference is hereby made to my application 115 Serial No. 664,537, gate equipment for railways, filed Sept. 24, 1923, allowed Dec. 24, 1924; and my application Serial No. 669,001, pump-unit for railway equipment, filed Oct. 15, 1923, and allowed May 12th, 1925. Both 120 of my said divisional applications were derived from my present application Serial No. 553,623 filed April 17, 1922.

Having fully described my invention what I claim as new and desire to secure by Let- 125 ters Patent is:

1. In a railway gate equipment, in combination with a reservoir containing oil under compressed air, and a pipe system for conveying oil; an engine cylinder, a pis- 130

ton slideable in the cylinder; air chambers adjacent to the respective ends of the cylinder; valves inter-communicating between the interior of the cylinder and the interior 5 of the respective air chambers; transfer pipes communicating with the interior of the cylinder, one on each side of the piston and communicating through the cylinder with diaphragm chambers in line with each 10 other; diaphragms in the respective diaphragm chambers; a bar connecting said diaphragms; an arm secured on said bar; a rod carried by said arm and effective to operate the valves adjacent to both air chambers, to transfer oil from the engine cylinder to the respective diaphragm chambers 15 to equalize pressure on the respective diaphragms in said diaphragm chambers.

2. An engine comprising a cylinder; a 20 piston slideable in the cylinder; spiders stationary in the cylinder, one on each side of the piston; perforated transfer tubes slideable in said spiders and adapted to transfer oil from one side of the piston to the other 25 side of the same piston according to the movement of the piston in the cylinder to equalize pressure on both sides of the piston.

3. In an installation of the class described, a reservoir containing oil and compressed air above the oil; a plurality of pipe lines receiving oil from the reservoir; hydraulic engines receiving oil from the pipe lines; and air domes at the terminals of said pipe lines.

35 4. In an equipment of the class described, the combination of a reservoir containing oil and compressed air above the oil; duplex pipe lines receiving oil from the reservoir; air domes at the terminals of said duplex pipe lines; a hydraulic motor actuated by fluid transmitted through said duplex pipe lines; air chambers co-acting with said motor to equalize fluid pressure within the motor; duplex series of wheel-actuated 40 pump-units receiving oil from the duplex pipe lines, each pump-unit comprising two pumps, one operative by car wheels going in one direction and the other operative by car wheels going in the opposite direction; and one receiving oil from one of said duplex pipe lines and delivering it into one end of the motor, and the other receiving oil from the other of said duplex pipe lines and delivering it into the other end of the 45 motor.

50 5. In an installation of the class described, the combination of a reservoir containing oil and compressed air above the oil; a plurality of pipe lines receiving oil from the reservoir; hydraulic motors receiving oil from the reservoir through the pipe lines; and wheel-actuated means for forcing fluid from the pipe lines into the 55 motors.

60 6. In an installation of the class described,

the combination of a hydraulic motor comprising a cylinder and a piston sliding therein; a reservoir containing fluid under pressure; a first pipe line communicating with one end of the motor cylinder; an air dome communicating with said first pipe line; a second pipe line communicating with the other end of the motor cylinder; an air dome communicating with said second pipe line; and car-wheel-actuated pumps adapted 70 to force fluid through the respective pipe lines against air pressure in the respective pipe lines against air pressure in the 75 respective air domes.

7. In a railway gate equipment, in combination with a reservoir containing fluid under compressed air, and a pipe system for conveying fluid; an engine cylinder, a piston slideable in the cylinder; air chambers adjacent to the respective ends of the cylinder; valves inter-communicating between the interior of the cylinder and the interior of the respective air chambers; transfer pipes communicating with the interior of the cylinder, one on each side of the piston 85 and communicating through the cylinder with diaphragm chambers in line with each other; diaphragms in the respective diaphragm chambers; a bar connecting said diaphragms; an arm secured on said bar; 90 a rod carried by said arm and effective to operate the valves adjacent to both air chambers, to transfer fluid from the engine cylinder to the respective diaphragm chambers to equalize pressure on the respective 95 diaphragms in said diaphragm chambers.

8. An engine comprising a cylinder; a piston slideable in the cylinder; spiders stationary in the cylinder, one on each side of the piston; perforated transfer tubes 105 slideable in said spiders and adapted to transfer fluid from one side of the piston to the other side of the same piston according to the movement of the piston in the cylinder to equalize pressure on both sides of the piston.

9. In an installation of the class described, a reservoir containing fluid and compressed air above the fluid; a plurality of pipe lines receiving fluid from the reservoir; hydraulic engines receiving fluid from the pipe 115 lines; and air domes at the terminals of said pipe lines.

10. In an installation of the class described, the combination of a reservoir containing fluid and compressed air above the fluid; a plurality of pipe lines receiving fluid from the reservoir; hydraulic motors receiving fluid from the reservoir through the pipe lines; and wheel-actuated means for forcing a fluid from the pipe lines into 120 the motors.

In witness whereof I have hereunto signed my name at Springfield, Illinois, this 15th day of April, 1922.

CHARLES W. BUTTRICK.
